[57] CLAIM

The ornamental design for a face plate for lighting control, as shown and described.

DESCRIPTION

FIG. 1 is a front elevational view of a face plate for lighting control showing our new design, the rear being unornamented;

FIG. 2 is an end elevational view thereof;

FIG. 3 is a top plan view thereof, the bottom being identical;

FIG. 4 is a front elevational view of a second embodiment of the design of FIG. 1, the only difference being the removal of the textured surface.

FIG. 1.

FIG. 2.

FIG. 3.

FIG. 4.
